BALL APPLICATOR ASSEMBLY WITH SHUTTLE-TYPE CLOSURE

Wilbur A. Schalch, Maumee, Ohio, assignor to Owens-Illinois Glass Company, a corporation of Ohio

Filed Jan. 4, 1961, Ser. No. 87,984
22 Claims. (Cl. 15—572)

The present application is a continuation-in-part of my application Serial No. 723,506, filed March 24, 1958, now abandoned, and the invention herein relates generally to a combination ball applicator and closure assembly for use with a dispensing container to facilitate roll-on application of various fluid and semi-fluid substances and preparations, and more particularly this invention relates to an assembly of the aforementioned type which is characterized by a shuttle-type closure or hood, which may be shifted or shuttled between alternative positions to respectively open and close the assembly and concurrently rotate the applicator ball without necessitating detachment of the closure from the assembly.

Ball-type applicator and container assemblies have in many instances in the past, found wide commercial acceptance as a convenient means of applying controlled amounts of various fluid and semi-fluid substances in a relatively smooth and uniform manner. However, to prevent a drying out, escape, or loss of the container's contents due to leakage, evaporation or other similar cause when the applicator is not being used, it has been customary practice to enclose the applicator within a closure, ordinarily having a generally conventional cup-shaped configuration which may be threadably or otherwise detachably fastened on the dispensing end of the container or the applicator assembly for axial movement relative to the applicator assembly. Obviously, in such conventional types of applicator assemblies, the closure must be completely removed from the applicator assembly or container prior to each use of the applicator. Frequently, the closure is misplaced or impaired, when removed from the assembly, and thereafter it usually becomes impossible to effectively prevent the objectionable drying out, escape, or loss of the container's contents. Thus, a substantial portion of the container's contents is frequently wasted. Also, such closures have frequently been somewhat ineffective to prevent a drying out of the container's contents, particularly residual portions of such contents remaining on the surface of the applicator or within the applicator assembly.

Another common characteristic of conventional ball-type applicator assemblies is that even after detachment and removal of the protective closure from the assembly, the applicator ball must ordinarily be rotated in order to moisten or lubricate the surface of the ball with the container's contents before application may be commenced.

Also it has been found that many types of fluids commonly applied in conjunction with such ball-type applicators possess extremely sticky or tacky properties and as a consequence of evaporation, dehydration or the like, form a hard rough residual coating on the surface of the applicator ball during the prolonged periods of time between each use of the applicator. Consequently, difficulty in subsequently obtaining a smooth and uniform application occurs. Further, when applying deodorants, medicants, colognes and the like onto the human body undesirable skin irritation may be occasioned by the resulting rough applicator surface. Another undesirable consequence attendant with the gradual build up or retention of residual fluid on the applicator surface is that the rotation of the applicator ball is frequently impeded or prevented.

Accordingly, it is an object of the present invention to provide an improved ball-type applicator and closure as-

2

sembly for use with a dispensing container, which obviates the undesirable necessity of removing and replacing the closure before and after each use of the applicator.

Another object of the present invention is to provide an improved applicator assembly which is particularly adapted to obviate the aforementioned undesirable consequences attendant with residual fluid remaining on the surface of the applicator after use.

Another object of the present invention is to provide an improved applicator assembly wherein opening movements of the closure effect a forceful rotation of the applicator ball to permit a premoistening or lubrication of the applicator ball prior to use.

Another object of the present invention is to provide an improved applicator assembly wherein closing movements of the closure effect a cleansing of residual fluid from the surface of the applicator ball.

Another object of the present invention is to provide an improved combination comprising a ball applicator, closure and dispensing container assembly characterized by the provision of a closure or hood, which is arranged for shuttle-like movement between alternate open and closed positions while retained in assembled relation, and which cooperates both to permit a smooth and uniform application of the container's contents and to effectively preclude undesirable and wasteful dissipation of the container's contents when the applicator is not being utilized.

A further object of the present invention is to provide an assembly capable of effecting the aforementioned objectives, and in such manner that the shuttle-like movement of the closure or hood occurs in a path intercepting an exposed portion of the applicating member and shifting same alternately between an applicating position and a sealed position, the latter position effectively precluding drying out, escape, or loss of the container's contents.

The specific nature of this invention, as well as other objects and advantages thereof, will become apparent to those skilled in the art from the following detailed description taken in conjunction with the annexed sheets of drawings on which, by way of example only, three preferred embodiments of this invention are illustrated.

Referring to the drawings:

FIG. 1 is a fragmentary elevational view of a dispensing container and showing in vertical central section on the neck of the container an applicator and closure assembly embodying the present invention and arranged in an open or applicating position.

FIG. 2 is a fragmentary side elevational view of the assembly shown in FIG. 1, with the closure being illustrated in vertical central section.

FIG. 3 is a view taken substantially along the line 3—3 in FIG. 1, with the applicating member being removed for purposes of clarity.

FIG. 4 is a view similar to FIG. 1, but for comparative purposes illustrating the assembly in closed non-applicating position.

FIG. 5 is a perspective view of the container neck portion with the closure and applicating member omitted from the drawing.

FIG. 6 is a fragmentary perspective view of a container neck portion embodying a modified form of the invention, and likewise having the closure omitted from the drawing for clarity of illustration.

FIGS. 7 and 8 are similar, respectively, to FIGS. 1 and 4 and illustrate further aspects of the embodiment shown in FIG. 6.

FIG. 9 is a sectional view taken along the plane 9—9 shown in FIG. 7, and for purposes of clarity the closure and applicating member have again been omitted from the drawing.

FIGS. 10—12 are views similar, respectively to FIGS. 7—9, showing another modified form of the invention.

FIG. 13 is a view similar to FIG. 4, and illustrating still another modified form of the invention and with the assembly being illustrated in closed position.

FIGURE 14 is a vertical view of the assembly shown in FIGURE 13, with the ball rotation section of the closure contacting the applicator ball and with the closure being depicted in section for clarity of illustration.

FIGURE 15 is a view taken substantially along the line 15—15 in FIGURE 14.

Briefly, the general arrangement of the principal components of the assembly, organized in applicating position, is shown in FIG. 1. As illustrated, a container 10 is provided, which is suitable for the retention of various fluid and semi-fluid substances and preparations. The container 10 includes a reduced diameter annular neck portion 10a having means therein forming a pocket in which to support an applicator ball 11 for universal rotatable movement. A generally U-shaped closure 12, which is pivotally attached to the sides of the container 10, forms a hood over the neck portion 10a and applicator ball 11 and confines the latter in assembled relation within the pocket. The closure 12 may be shuttled back and forth over the applicator ball 11 between an open applicating position (FIG. 1), in which position the applicator ball 11 is capable of transferring a smooth and uniform film of the container's contents when rolling motion is imparted thereto, and a closed non-applicating position (FIG. 4), which precludes a drying up, leakage, evaporation or other similar loss or waste of the container's contents when the assembly is not being used for applicating purposes.

In greater detail, container 10, which is preferably fabricated from glass or other material, such as plastic, metal, or the like, suitable for the retention of various fluid and semi-fluid substances, includes a dispensing opening 10b, defined by the interior surface of the annular neck portion 10a, and, forms a passage through which the container's contents flow and contact the surface of the applicator ball 11 when the container 10 is inverted preparatory to use. Internally of the neck portion 10a and in the region of the inner end thereof, the dispensing opening 10b is partially restricted and defines a pocket 10c in which to gravitationally support the applicator ball 11 for universal rotatable motion. As illustrated in FIG. 3, this restriction of the dispensing opening 10b is formed by projections 10d which extend radially inward from the wall of the dispensing opening; and, although one projection may be sufficient in certain instances, at least three such projections arranged in substantially evenly spaced relationship are usually preferable. Additionally, the projections 10d may be integrally formed with the wall of the dispensing opening, as illustrated in FIGS. 1-4, or may be formed independently thereof and inserted in the dispensing opening, as in a manner to be subsequently described in relation to the modified forms of this invention illustrated in FIGS. 5-15. Pins 10f are integrally formed on or otherwise affixed to opposite exterior sides of the container 10 and provide a pivotal mounting for pivotal or shuttle-like movement of the U-shaped closure 12. The outer end of the neck portion 10a defines an annular rim 10e having an upwardly facing surface upon which the closure 12 may slide and which is shaped in the form of a cylindrical segment having an axis of radial symmetry normal to and intersecting the axis of the dispensing opening 10a and coinciding with the pivotal axis defined by pins 10f.

The applicator ball 11, which serves to transfer a smooth and uniform coating of the container's contents, is fabricated from a resiliently deformable material such as rubber, polyethylene, or other material or materials having similar characteristics of resiliency, pliability, sealability and the like, and is sufficiently resilient that a compressive force substantially in excess of that normally imposed upon the applicator ball 11 during ordinary application will deform or distend the ball in the manner

shown in FIG. 4 and cause same to engage the wall of the pocket 10c in fluid impervious sealed relationship, as for example at 10h.

The closure 12 is preferably constructed from a plastic material such as polystyrene, but may likewise be constructed of metal or other resiliently deformable material which is resistant to corrosion when exposed to the contents of the container and which possesses a greater degree of rigidity than the applicator ball 11. The closure ball 11. The closure 12 is characterized by a U-shaped hood-type construction which, as previously mentioned, overlies the rim 10e of the container neck portion 10a, and which may be moved transversely across the dispensing opening 10b in shuttle-like manner between alternative open and closed positions. The closure 12 includes: a rim or bight portion 12a having a cylindrical bottom or underside cam surface 12b mating with the cylindrical segment end surface portion of the rim 10e on the container neck portion 10a, a pair of depending side walls 12c spaced in parallelism along opposite sides of the container neck portion 10a and, respectively, defining transverse openings 12d located at the geometrical axis of the cylindrical bight portion 12a which, respectively receive pins 10f for pivotal or shuttle-like movement of the closure 12 on the container 10. The closure 12 may be readily mounted on pins 10f by distending the resilient side walls 12c of the closure sufficiently to permit the pins 10f to be snapped into the transverse openings 12d. The mating configuration of the cam surface 12b and the end surface of the rim 10e permits pivotal sliding movement of the bight portion 12a of the closure along the rim 10e of the container 10 while retaining a frictional seal therebetween which precludes leakage or seepage of the container's contents from around the outer end of the container neck portion 10a. The cam surface 12b is thus disposed in a path intercepting the protruding or exposed portion 11a of the applicator ball 11. Also included on the underside of the closure 12 and defined on the cam surface 12b in a location spaced along the pivotal axis of the closure there may be provided a recess 12g which receives an upper portion of the deformed applicator ball 11 when the closure is pivoted or shuttled to its closed position.

From the foregoing description it will be readily apparent that with the closure 12 positioned as in FIG. 1, with the protruding portion 11a of the applicator ball 11 protruding through the discharge orifice 12f, the container's contents may be applied in a smooth and uniform manner by merely bringing the applicator ball 11 into rolling contact with the surface to which application is desired, realizing of course that the container should be first inverted or shaken in order to moisten the surface of the applicator ball with the container's contents. It will likewise be apparent that when application is not desired the closure 12 may be shuttled to a closed position, shown in FIG. 4, wherein the cam surface 12b frictionally slides on the rim 10e of the container neck portion 10a and overrides the applicator ball 11, thus compressing the applicator ball against the projections 10d and causing it to deform and distend radially outward into sealing engagement with the wall of the pocket 10c to form a fluid-impervious annular seal as at 10h, which extends continuously around the pocket and prevents leakage or evaporation of the container's contents. Likewise the recessed portion 12g of the arcuate rim 12b will permit a portion of the compressed applicator ball 11 to snap therein and retain the closure 12 in closed position until it is manually shuttled back to its open position and, thus, help to avoid the possibility of accidentally opening the closure, as when the assembly is being carried in a lady's handbag or the like.

In the modified embodiment of the invention illustrated in FIGS. 6-9, there is illustrated a container 15 having a conventional reduced diameter neck portion 15a. Inserted in the neck portion 15a of the container 15, there

is a rigid annular sleeve 16 which is preferably constructed from polystyrene, or other rigid plastic, glass, or metallic material. The sleeve 16 includes a radial external flange 16a located at the outer end of the sleeve and which seats firmly on the rim 15e of the neck portion 15a, and prevents the sleeve 16 from being displaced into the container. On the interior surface of the sleeve 16 there are a plurality of spaced inwardly directed projections 16b, best shown in FIG. 7, which restrict the interior bore of the sleeve 16 and define a pocket 16c in which the applicator ball is loosely confined for universal rotational movement when the closure is in an open position, as shown in FIG. 7. The upper surface of the radial flange 16a defines a cylindrical segment surface centered on pins 10f to provide a continuous contact with the underside of the arcuate rim 12a of the closure 12 and to form a sliding frictional seal therewith, similar in purpose and manner to the seal between the rim 10e of the container 10 and the closure 12 described in the first-mentioned embodiment of this invention. In this instance also, the applicator ball 11 is fabricated from a resilient, deformable material, which is compressed into sealing engagement with the wall of the pocket 16c, as at 16d, when the closure 12 is shuttled to its closed relative position, illustrated in FIG. 8.

In FIGS. 10-12 there is illustrated still another embodiment of this invention. In this embodiment a rigid applicator ball 17, which may be fabricated from glass, polystyrene, metal, or the like, replaces the resilient, deformable ball described in the previous two embodiments. In this latter embodiment an annular fitment 18, in all essential respects identical in external appearance to the sleeve 16 shown in FIG. 5, is snugly inserted in the neck of container 15 and houses the applicator ball 17. The fitment 18 is fabricated from polyethylene, or other material having similar characteristics of resiliency, softness, and sealability, and is shaped to fit snugly within the neck 15a of the container. A radial external shoulder 18a seats on the rim of the container. Defined within the fitment 18 and positioned beneath a lower chordal segment of the applicator ball 17, there is a continuous annular sealing surface 18b, best illustrated in FIG. 10. A flexible resilient internal projection is provided, such as for example a diametrical rib 18c extending transversely across the bore of the fitment 18, and normally supports the ball 17 in an elevated position relative to sealing surface 18b. The radial shoulder 18a, like the flange 16a in FIGS. 6-9, is formed with an upper surface configuration shaped to define a cylindrical segment providing continuous sliding contact between the fitment and the underside of the closure 12.

In its functional aspect, the diametrical rib 18c supports the applicator ball 17 in a position elevated from the sealing surface 18b and with an outer segment of the applicator ball 17a protruding through the discharge orifice 12f in the closure 12, when the closure 12 is in its open or applicating position shown in FIG. 10. However, when the closure 12 is pivoted or shuttled to its closed position, as shown in FIG. 11, the closure 12 depresses the applicator ball 17 causing the resilient rib to yield inwardly until the applicator ball 17 is firmly sealed against the annular sealing surface 18b. In reverse manner, when the closure is pivoted or shuttled to its open position, FIG. 10, the diametrical rib 18c, which although resilient and flexible is sufficiently rigid to resist the pressures ordinarily imposed upon the applicator ball during application of the container's contents, resiliently lifts the applicator ball away from the sealing surface 18b and into application position.

An additional inherent function of all of the foregoing embodiments of the present invention is more particularly evident in the modified form of the invention illustrated in FIGS. 13-15. In this respect, it will be observed in the foregoing embodiments that as the closure

is shuttled between its alternate open and closed positions and intercepts the protruding portion of the applicator ball it will naturally tend to rotate the applicator ball. Thus, as the closure is shuttled from a closed to an open position the transverse frictional movement of the closure in contact with the protruding surface of the applicator ball produces a forceful rotation of the applicator ball as the latter is gradually displaced from sealing contact with the wall of the container neck (FIGS. 1-5) or the wall of the fitment (FIGS. 6-12). Thus, the applicator ball is subjected to sufficient forceful rotation attendant with the opening of the closure to overcome the frequent undesirable tendency of the applicator ball to adhere to the wall of the container or fitment when used in conjunction with various sticky, tacky or adhesive fluids, such as mucilage, and certain types of deodorants, medicants, and the like. Furthermore, the rotation of the applicator ball attending the opening movement of the closure occasions a surface pre-moistening or pre-lubrication of the applicator ball with the contents of the container which are entrapped within the fitment or container neck when the applicator assembly is closed. Such pre-moistening and pre-lubrication may likewise be achieved by inverting the container during the opening movement of the closure.

Likewise, the closure imparts a rotational movement to the applicator ball when it is shuttled to a closed position, and as the applicator ball is concurrently forced gradually into contact with the sealing surface in the container neck or fitment the sealing surface imparts a wiping action to the surface of the applicator ball and cleanses residual fluid from the surface of the applicator ball.

The modified form of the invention shown in FIGS. 13-15 is adapted to achieve a more pronounced rotation 30 of the applicator ball during alternate opening and closing movements of the closure; and consequently is capable of providing a more effective pre-moistening or pre-lubrication and cleansing of the applicator ball when such functions are desirable. More particularly referring to FIG. 13, it will be observed that the applicator ball 17, as illustrated, may be of rigid construction, as in FIGS. 10-12. Also the applicator ball may be of resilient construction such as the applicator ball 11 shown in FIGS. 6-12. The applicator ball is confined in ball and socket relationship within an annular fitment 19 similar in construction with the previously described fitment 18, but additionally having means adjacent the applicating end thereof for confining the applicator ball within the fitment independently of the closure 20. Such means may be in the form of one or more integral inwardly protruding tabs 19d which constrict the open applicating end of the fitment 19 to a size sufficient to retain the medial portion of the applicator ball loosely within the confines of the fitment. In other respects the fitment 19 may be similar 50 with the fitment 18. For example, the fitment 19 may be fabricated from polyethylene and is shaped to fit snugly within the neck of the container 15 with a radial external shoulder 19a, best illustrated in FIG. 14, seating upon the neck rim of the container in sealing relationship as at 19e. Within the fitment and located beneath a lower chordal segment of the applicator ball 17 there is formed a continuous annular sealing surface 19b. A flexible internal projection, or diametrical web 19c resiliently supports the applicator ball 11 and accommodates depression 55 of the applicator ball into sealing contact with the sealing surface 19b when the closure is shifted to a closed position, as shown in FIG. 13. An arcuate sealing surface 19f is provided along the upper face of the rim 19a and the tabs 19d to form a sliding sealed surface on which the closure 20 may be shifted between its alternative open and closed positions.

The U-shaped closure 20, like the previously described closure 12 is mounted upon pins or the like on the side of the container 20 for shuttle-like pivotal movement between alternative open and closed positions and is prefer-

ably constructed from a rigid plastic or metallic material having good corrosion resistance. In closed and sealed position the closure 20 functions in essentially the same manner as the previously described embodiment shown in FIGS. 10-12. In this respect, and as shown in FIG. 13, the arcuate bight portion of the closure 20 is provided with a cam section 20a which slides in sealing relationship, as at 20c along the upper arcuate surface of the fitment and intercepts and depresses the applicator ball 17 downwardly upon the diametrical web 19c and into sealed continuous peripheral contact with the sealing surface 19b. By comparison however, the bight portion of the closure 20 is imperforate and is shifted completely to one side of the applicator ball 17 to open the assembly and expose the applicator ball for use, as shown in broken lines in FIG. 15. Also, the bight portion of the closure 20 is provided with a ball rotating section 20b which defines a recessed surface area 20e extending along a segment of the ball contacting underside surface of the closure bight portion. The recessed surface 20e preferably has a knurled or otherwise roughened finish and is of sufficient depth to permit the diametrical web 19c to resiliently elevate the applicator ball out of sealing contact with the sealing surface 19b while still restraining the applicator ball 17 in a depressed position intermediate its normal fully elevated applying position and fully depressed sealed position and as shown in solid lines in FIG. 15. Thus, as the closure 20 is shifted from a closed to an open position the applicator ball 17 is gradually lifted out of sealing contact with sealing surface 19b and is brought into frictional contact with the recessed surface 20e in the ball rotating section 20a of the closure 20 and is forcefully rotated under the influence of the frictional contact of the closure with the applicator ball. Conversely, the applicator ball is rotated as the closure is shifted from an open to a closed position and as the cam section 20a gradually forces the rotating applicator ball 17 against the sealing surface 19b residual fluid is wiped from the surface of the ball. Preferably, and as illustrated, the ball rotating section 20b is formed on the end of the closure which corresponds to the trailing end of the closure as it is shifted from a closed to an open position. Also, the closure may be provided with a stop, as at 15b, which governs the extent of pivotal movement of the closure between open and closed positions and is arranged to engage the rim of the container 15 when the closure is fully closed and to rest against the side of the container when the closure is fully opened.

Although, the modified form of the invention shown in FIGS. 13-15, has been illustrated in a preferred embodiment in conjunction with a rigid applicator ball and a fitment, it is understood that the imperforate closure therein shown and described may likewise be employed with a resiliently deformable applicator ball and/or with a container neck portion having integral projections forming a socket for the applicator ball merely by providing the container neck portion or fitment with tabs similar to tabs 19d or other suitable ball restricting means capable of retaining the applicator ball in assembly when the closure is shifted to an open position.

In any event the ball rotation effected as an incident of opening and closing the closure, permits the full surface of the applicator ball to be pre-moistened with the contents of the container during opening and causes the surface of the applicator to be wiped clean during closing. Also, the forceful rotation occasioned during opening of the closure frees the applicator ball from its frequent tendency to freeze or adhere to the surface of its confining element.

Among other advantages, the present invention provides a ball-type applicator assembly having a novel closure which is not subject to being lost or misplaced, and which permits the applicator assembly to be opened and closed in a more convenient manner, since it is not necessary to remove and replace the closure before and after

each use of the applicator. Also, the forceful rotation imparted to the applicator ball by the cam surface on the underside of the bight portion of the closure overcomes the frequent tendency of the applicator ball to adhere to the surface of the confining socket so as to provide free rotation of the applicator ball when the closure is shuttled to an open position. Additionally, the surface of the applicator ball may be pre-moistened or pre-lubricated with the container's contents by merely inverting the container while the closure is being opened. Conversely, a forceful rotation imparted to the applicator ball when the closure is shuttled to a closed position causes the ball to be wiped substantially clean of residual fluid as it is pressed and rotated against the sealing surface defined within the ball confining element.

It will, of course, be understood that various details of construction may be modified throughout a wide range without departing from the principles of this invention, and it is not, therefore, the purpose to limit the patent granted hereon otherwise than as necessitated by the scope of the appended claims.

1 claim:

1. The combination of: a dispensing container defining a dispensing opening communicating with the interior of the container; means partially restricting said dispensing opening and forming a pocket therein; an applicator ball loosely resting within said pocket and having an outer segment protruding axially outward from said container; at least one of the members of the group consisting of said restricting means and said applicator ball having a resilient and flexible construction to accommodate depression of said applicator ball into said pocket; a closure overlying said dispensing opening and carried by said container for shuttle-like movement across said dispensing opening between alternative open and closed positions relative to said dispensing opening, said closure defining an orifice diametrically smaller than said applicator ball and traversed by said outer segment of said applicator ball when said closure is in said open position, said closure also defining a cam surface intercepting said outer segment of said applicator ball and depressing said applicator ball into an enclosed position within said pocket when said closure is in said closed position.

2. The combination of: a dispensing container having a dispensing opening communicating with the interior of the container; means partially restricting said dispensing opening and forming a pocket therein; an applicator ball loosely resting within said pocket and having an outer segment protruding axially outward from said container; at least one of the members of the group consisting of said restricting means and said applicator ball having a resilient and flexible construction to accommodate depression of said application ball into said pocket; a closure overlying said dispensing opening and pivotally mounted for shiftable shuttle-like movement across said dispensing opening between alternative open and closed positions relative to said dispensing opening; said closure defining an orifice diametrically smaller than said applicator ball and traversed by said outer segment of said applicator ball when said closure is in said open position, and said closure also defining a cam surface intercepting said outer segment of said applicator ball and depressing said applicator ball into sealing contact with the wall of said pocket when said closure is in said closed position.

3. The combination of: a dispensing container having a neck portion defining a dispensing opening communicating with the interior of the container; means located within said neck portion partially restricting said dispensing opening and forming a pocket therein; a resiliently de-

formable applicator ball loosely resting within said pocket and having an outer segment protruding axially outward from said neck portion; a closure overlaying said neck portion and pivotally mounted for shuttle-like movement across said neck portion between alternative open and closed positions relative to said dispensing opening,

said closure defining an orifice diametrically smaller than said applicator ball and receiving said outer segment of said applicator ball therethrough when said closure is in said open position, and said closure also defining an interior cam surface intercepting said outer segment of said applicator ball and thereby deforming said applicator ball into an enclosed position within said pocket when said closure is in said closed position.

4. The combination of: a dispensing container having a neck portion defining a dispensing opening communicating with the interior of the container; means disposed within said neck portion partially restricting said dispensing opening and forming a pocket therein; the wall of said pocket defining a continuous annular sealing surface surrounding said pocket; an applicator ball loosely resting within said pocket, at least one of the members of the group consisting of said restricting means and said applicator ball having a resilient and flexible construction to accommodate depression of said applicator ball into said pocket, said applicator ball having an inner segment overlying said sealing surface and having an outer segment protruding axially outward from said neck portion; a closure overlying said neck portion and pivotally mounted for shuttle-like movement across said neck portion between alternative open and closed positions relative to said dispensing opening, said closure defining an orifice diametrically smaller than said applicator ball and receiving said outer segment of said applicator ball therethrough when said closure is in said open position, and said closure also defining an interior cam surface intercepting said outer segment of said applicator and depressing said applicator ball into sealing contact with said annular sealing surface when said closure is in said closed position.

5. The combination of: a dispensing container having a neck portion defining a dispensing opening communicating axially with the interior of the container; and annular rim surrounding the outer axial end of said dispensing opening defining an outwardly facing end surface, said end surface being arcuate about an axis normal to and intersecting the axis of said dispensing opening; an applicator ball loosely resting within said pocket and having an outer segment protruding axially outward from said dispensing opening; means partially restricting said dispensing opening and forming a pocket therein; at least one of the members of the group consisting of said restricting means and said applicator ball having a resilient and flexible construction to accommodate depression of said applicator ball into said pocket; a closure pivotally carried by said container for shuttle-like movement across said neck portion between alternative open and closed positions relative to said dispensing opening, said closure pivotal axis coinciding with said axis of said arcuate end surface, said closure having an arcuate surface concentric with and frictionally contacting said arcuate end surface of said annular rim, said closure also defining an orifice through said arcuate surface and restricted in size for receiving said outer segment only of said applicator ball therethrough when said closure is in said open position, and a cam surface on said closure intercepting said outer segment of said applicator ball and depressing said applicator ball into an enclosed position within said pocket when said closure is in said closed position.

6. The combination of: a dispensing container having a neck portion defining a dispensing opening communicating with the interior of the container; means for partially obstructing the inner axial end of said dispensing opening and for forming a pocket therein; an applicator ball loosely resting within said pocket and having an outer segment protruding outwardly from said container, at least one of the members of the group consisting of said restricting means and said applicator ball having a resilient and flexible construction to accommodate depression of said applicator ball into said pocket; a U-shaped closure overlying said dispensing opening having a bight portion

spacing oppositely facing depending side walls, said side walls being mounted for shuttle-like movement of said bight portion across said neck portion between alternative open and closed positions relative to said dispensing opening, said bight portion defining an orifice diametrically smaller than said applicator ball and arranged to receive said outer segment of said applicator ball therethrough when said closure is in said open position and having a surface portion arranged to intercept said outer segment of said applicator ball and depress said applicator ball into an enclosed position within said pocket when said closure is in said closed position.

7. The combination of: a dispensing container having a neck portion defining a dispensing opening communicating axially with the interior of the container; an annular rim on the outer end of said neck portion surrounding said dispensing opening, said rim defining a convex outwardly facing end surface having an axis of radial symmetry normal to and intersecting the axis of said dispensing opening; means partially restricting said dispensing opening and forming a pocket therein; a resiliently deformable applicator ball loosely resting within said pocket and having an outer segment protruding axially outward from said neck portion; a closure overlying said dispensing opening and pivotally carried by said container for shuttle-like movement across said neck portion between alternative open and closed positions relative to said dispensing opening, said closure pivotal axis coinciding with said axis of radial symmetry of said end portion, said closure having an interior surface concentric with and contacting said end surface of said annular rim in continuous frictional sealing relation, said closure also defining an orifice smaller in size than said applicator ball and receiving said outer segment of said applicator ball therethrough when said closure is in said open position and having a cam surface intercepting said outer segment of said applicator ball and deforming said applicator ball into an enclosed position within said pocket when said closure is in said closed position.

8. The combination of: a dispensing container having a neck portion defining a dispensing opening communicating with the interior of the container; an annular rim on the outer end of said neck portion surrounding said dispensing opening, said rim defining a convex outwardly facing end surface having an axis of radial symmetry disposed normal to and intersecting the axis of said dispensing opening; means partially restricting said dispensing opening and forming a pocket therein; a resiliently deformable applicator ball loosely resting within said pocket and having an outer segment protruding axially outward from said neck portion; a U-shaped closure having a bight portion overlying said neck portion and having depending side walls straddling said neck portion, said side walls being pivotally carried by said container, said pivotal axis coinciding with the axis of radial symmetry of said end surface of said rim for shuttle-like movement of said bight portion across said dispensing opening between alternative open and closed positions, said bight portion having an arcuate surface concentric with said contacting said arcuate end surface of said rim in continuous frictional sealing relation, and said bight portion also defining an orifice smaller in size than said applicator ball and receiving said outer segment of said applicator ball therethrough when said closure is in said open position, and a cam surface on said closure intercepting said outer segment of said applicator ball and deforming said applicator ball into sealing contact with the wall of said pocket when said closure is in said closed position.

9. The combination of: a dispensing container having a neck portion defining a dispensing opening communicating with the interior of the container; an annular sleeve disposed within said neck portion partially restricting said dispensing opening and forming a pocket therein; an applicator ball loosely resting within said pocket and having an outer segment protruding axially outward from

said neck portion; at least one of the members of the group consisting of said restricting means and said applicator ball having a resilient and flexible construction to accommodate depression of said applicator ball into said pocket; a closure overlying said neck portion; means for shiftably mounting said closure on said container for shuttle-like movements across said neck portion between alternative open and closed positions relative to said dispensing opening; said closure defining an orifice smaller in size than said applicator ball and receiving said outer segment of said applicator ball therethrough when said closure is in said open position, and said closure also having a cam surface intercepting said outer segment of said applicator ball and depressing said applicator ball into an enclosed position within said pocket when said closure is in said closed position.

10. The combination of: a dispensing container having a neck portion defining a dispensing opening communicating with the interior of the container; an annular sleeve element disposed within said neck portion and having means therein partially restricting said dispensing opening and forming a pocket therein, said sleeve having a radial rim jutting over the outer end of said neck portion; an applicator ball loosely resting within said pocket and having an outer segment protruding axially outward from said neck portion, said applicator ball being constructed from a resiliently deformable material; a closure overlying said rim; means pivotally connecting said closure to the exterior of said container for shuttle-like movement of said closure across said rim between alternative open and closed positions relative to said dispensing opening; said closure defining an orifice smaller in size than said applicator ball and receiving said outer segment of said applicator ball therethrough when said closure is in said open position, and said closure also defining an interior cam surface intercepting said outer segment of said applicator ball and deforming said applicator ball into an enclosed position within said pocket when said closure is in said closed position.

11. The combination of: a dispensing container having a neck portion defining a dispensing opening communicating with the interior of the container; an annular sleeve located within said neck portion partially restricting said dispensing opening and forming a pocket therein, said sleeve having a radial rim jutting over the outer end of said neck portion and defining an arcuate outwardly facing end surface having an axis of radial symmetry normal to and intersecting the axis of said dispensing opening; an applicator ball loosely resting within said pocket and having an outer segment protruding axially outward from said neck portion; at least one of the members of the group consisting of said annular sleeve and said applicator ball having a resilient and flexible construction to accommodate depression of said applicator ball into said pocket; a closure pivotally carried by said container for shuttle-like movement across said neck portion between alternative open and closed positions relative to said dispensing opening, said closure having an arcuate surface concentric with and contacting said arcuate end surface of said radial rim in continuous frictional sealing relation, said closure also defining an orifice through said arcuate surface of restricted size for receiving said outer segment only of said applicator ball therethrough when said closure is in said open position, and an interior cam surface on said closure intercepting said outer segment of said applicator ball and depressing said applicator ball into an enclosed position within said pocket when said closure is in said closed position.

12. The combination of: a dispensing container having a neck portion defining a dispensing opening communicating with the interior of the container; an annular sleeve located within said neck portion partially restricting said dispensing opening and forming a pocket therein, said sleeve having a radial rim jutting over the outer end of said neck portion and defining an arcuate outwardly

facing end surface having an axis of radial symmetry normal to and intersecting the axis of said dispensing opening; a resiliently deformable applicator ball loosely resting within said pocket and having an outer segment protruding axially outward from said neck portion; a closure pivotally carried by said container for shuttle-like movement across said neck portion between alternative open and closed positions relative to said dispensing opening, said closure having an arcuate surface concentric with and contacting said arcuate end surface of said radial rim in continuous frictional sealing relation, said closure also defining an orifice through said arcuate surface of smaller size than said applicator ball and receiving said outer segment of said applicator ball therethrough when said closure is in said open position, and an interior cam surface on said closure intercepting said outer segment of said applicator ball and deforming said applicator ball into said dispensing opening and into sealing contact with the wall of said pocket to seal said dispensing opening when said closure is in said closed position.

13. The combination of: a dispensing container defining a dispensing opening communicating with the interior of the container; an annular fitment disposed within said dispensing opening, said fitment having at least one resilient inwardly projecting shoulder partially restricting said dispensing opening and forming a pocket therein; a rigid applicator ball loosely resting within said pocket and having an outer segment protruding axially outward from said neck portion; a closure overlying said dispensing opening; means for shiftably mounting said closure on said container for shuttle-like movement between alternative open and closed positions relative to said dispensing opening; said closure defining an orifice of smaller size than said applicator ball and receiving said outer segment of said applicator ball therethrough when said closure is in said open position, and said closure also defining an interior cam surface intercepting said outer segment of said applicator ball and depressing said applicator ball against said resilient shoulder and into an enclosed position within said pocket when said closure is in said closed position.

14. The combination of: a dispensing container having a neck portion defining a dispensing opening communicating with the interior of the container; an annular fitment of elastomeric material telescoped within said neck portion, said fitment having at least one inwardly projecting shoulder partially restricting said dispensing opening and forming a pocket therein and having a radial flange forming a rim overlying the outer end of said neck portion; a rigid applicator ball loosely resting within said pocket and having an outer segment protruding axially outward from said rim; a closure overlying said neck portion and pivotally mounted for shuttle-like movement across said rim between alternative open and closed positions relative to said dispensing opening; said closure defining an orifice diametrically smaller than said applicator ball and receiving said outer segment of said applicator ball therethrough when said closure is in said open position, and said closure defining an interior cam surface intercepting said outer segment of said applicator ball and depressing said applicator ball against said shoulder and into sealing contact with the wall of said pocket when said closure is in said closed position.

15. The combination of: a dispensing container having a neck portion defining a dispensing opening communicating with the interior of the container; an annular fitment telescoped within said neck portion, said fitment having at least one resilient inwardly projecting shoulder partially restricting said dispensing opening and forming a pocket therein and having a radial flange forming a rim overlying the outer end of said neck portion, said flange defining an arcuate outwardly facing end surface having an axis of radial symmetry normal to and intersecting the axis of said dispensing opening; a rigid applicator ball loosely resting within said pocket and having

an outer segment protruding axially outwardly from said neck portion; a closure overlying said neck portion and pivotally carried by said container for shuttle-like movement across said radial flange between alternative open and closed positions relative to said dispensing opening, said closure having an arcuate surface concentric with and contacting said arcuate end surface of said radial flange in continuous frictional sealing relation, said closure also defining an orifice through said arcuate surface, said orifice being of smaller size than said applicator ball and receiving said outer segment of said applicator ball therethrough when said closure is in said open position, and a cam surface intercepting said outer segment of said applicator ball and depressing said applicator ball against said resilient shoulder and into an enclosed position within said pocket when said closure is in said closed position.

16. The combination of: a dispensing container having a neck portion defining a dispensing opening communicating with the interior of the container; an annular fitment telescoped within said neck portion, said fitment having at least one resilient inwardly projecting shoulder partially restricting said dispensing opening and forming a pocket therein and having a radial flange forming a rim overlying the outer end of said neck portion, said flange defining an arcuate outwardly facing end surface having an axis of radial symmetry normal to the axis of said dispensing opening; a rigid applicator ball loosely resting within said pocket and having an outer segment protruding axially outward from said neck portion; a closure overlying said neck portion and pivotally mounted for shuttle-like movement across said radial flange between alternative open and closed positions relative to said dispensing opening; said closure having an interior surface concentric with and contacting said outwardly facing end surface of said radial flange in continuous frictional sealing relation, said closure also defining an orifice smaller in size than said applicator ball and receiving said outer segment of said applicator ball therethrough when said closure is in said open position, and an interior cam surface intercepting said outer segment of said applicator ball and depressing said applicator ball against said resilient shoulder and into sealing contact with the wall of said pocket when said closure is in said closed position.

17. The combination of: a dispensing container having a neck portion defining a dispensing opening communicating with the interior of the container; an annular fitment telescoped within said neck portion, said fitment having at least one resilient inwardly projecting shoulder partially restricting said dispensing opening and forming a pocket therein and having a radial flange forming an annular rim overlying the outer end of said neck portion, said annular rim defining an arcuate outwardly facing end surface having an axis of radial symmetry normal to the axis of said dispensing opening, a rigid applicator ball loosely resting within said pocket and having an outer segment protruding axially outward from said neck portion; a continuous annular sealing surface defined by the wall of said pocket and spaced beneath a peripheral segment of said applicator ball; a closure overlying said neck portion and pivotally mounted for shuttle-like movement across said radial flange between alternative open and closed positions relative to said dispensing opening, said closure defining an orifice of smaller size than said applicator ball and receiving said outer segment of said applicator ball therethrough when said closure is in said open position, and said closure having an interior surface concentric with and contacting said outwardly facing end surface of said radial flange in continuous frictional sealing relation, said closure also defining an interior cam surface intercepting said outer segment of said applicator ball and depressing said applicator ball against said resilient shoulder and into sealing contact with said sealing surface when said closure is in said closed position.

18. The combination of: a dispensing container defin-

ing a dispensing opening communicating with the interior of the container; means partially restricting said dispensing opening and forming a pocket in communication with said container with the pocket being the only passage for fluid passing out through said dispensing opening; an applicator ball loosely resting within said pocket and having an outer segment protruding axially outward from said container; at least one of the members of the group consisting of said restricting means and said applicator ball having a resilient construction to accommodate depression of said applicator ball into said pocket; a closure, means mounting said closure in overlying relationship with said dispensing opening for shuttle-like movement thereacross between alternative open and closed positions, said closure defining an opening of smaller size than said applicator ball and receiving said outer segment of said applicator ball therethrough when said closure is in said open position, said closure also defining a cam surface intercepting said outer segment and depressing said applicator ball into said pocket closing said dispensing opening when said closure is in said closed position.

19. The combination of: a dispensing container defining a dispensing opening communicating with the interior of the container; means partially restricting said dispensing opening and forming a pocket in communication with said container with the pocket being the only passage for fluid passing out through said dispensing opening; an applicator ball loosely resting within said pocket and having an outer segment protruding axially outward therefrom; at least one of the members of the group consisting of said restricting means and said applicator ball having a resilient construction to accommodate depression of said applicator ball into said pocket; a closure, means mounting said closure in overlying relationship with said pocket for shuttle-like movement thereacross between alternative open and closed positions, said closure defining an opening of smaller size than said applicator ball and receiving said outer segment of said applicator ball therethrough when said closure is in said open position, said closure also defining a cam surface intercepting said outer segment and depressing said applicator ball into said pocket closing said dispensing opening when said closure is in said closed position.

20. The combination of: a dispensing container defining a dispensing opening communicating with the interior of the container; means partially restricting said dispensing opening and forming a pocket in communication with said container with the pocket being the only passage for fluid passing out through said dispensing opening; an applicator ball loosely confined within said pocket and having an exposed outer segment protruding axially outward therefrom; at least one of the members of the group consisting of said restricting means and said applicator ball having a resilient construction to accommodate depression of said applicator ball into said pocket; a closure, means mounting said closure in overlying relationship with said pocket for shuttle-like movement thereacross between alternative open and closed positions, said closure defining a cam surface intercepting said outer segment and depressing said applicator ball in said pocket closing said dispensing opening when said closure is in said closed position and intercepting and rotating said applicator ball when said closure is shuttled towards said open position.

21. The combination of: a dispensing container defining a dispensing opening communicating with the interior of the container; means partially restricting said dispensing opening and forming a pocket in communication with said container with the pocket being the only passage for fluid passing out through said dispensing opening; an applicator ball loosely confined within said pocket and having an outer segment protruding axially outward therefrom; at least one of the members of the group consisting of said restricting means and said applicator ball having a resilient construction to accommodate depression of said applicator ball into said pocket; a closure,

means mounting said closure in overlying relationship with said pocket for shuttle-like movement thereacross between alternative positions opening and closing said pocket, said closure defining a cam surface intercepting said outer segment and rotating and depressing said applicator ball in said pocket when said closure is shuttled across said pocket between said opening and closing positions.

22. The combination of: a dispensing container defining a dispensing opening communicating with the interior of the container; means partially restricting said dispensing opening and forming a pocket therein; an applicator ball loosely confined within said pocket and having an outer segment protruding axially outward from said pocket; a closure, means mounting said closure in

5

15

overlying relationship with said pocket for shuttle-like movement thereacross between alternative open and closed positions, said closure defining a cam surface intercepting said outer segment and rotating said applicator ball within said pocket when said closure is shuttled across said pocket between said open and closed positions.
